UNITED STATES PATENT OFFICE.

MAX KLINE, OF NEW YORK, N. Y.

DESIGN FOR A BELT BUCKLE.

Application filed March 18, 1924. Serial No. 8,979. Term of patent 3½ years.

To all whom it may concern:

Be it known that I, MAX KLINE, a citizen of the United States, and a resident of the city of New York, borough of the Bronx, in the county of Bronx and State of New York, United States of America, have invented a new, original, and ornamental Design for Belt Buckle, of which the following is a specification, reference being had

to the accompanying drawings, forming part thereof.

Figure 1 is a plan view of a belt buckle embodying my new design.

Figure 2 is a longitudinal sectional view.

I claim:

The ornamental design for a belt buckle, as shown.

MAX KLINE.
